UNITED STATES PATENT OFFICE.

MICHAEL JOSEPH CARNEY, OF KEWANEE, ILLINOIS.

BOILER.

1,169,065.

Specification of Letters Patent. Patented Jan. 18, 1916.

Application filed August 7, 1915. Serial No. 44,320.

To all whom it may concern:

Be it known that I, MICHAEL JOSEPH CARNEY, a citizen of the United States, residing at Kewanee, in the county of Henry and State of Illinois, have invented certain new and useful Improvements in Boilers, of which the following is a specification.

My invention has reference to boilers, and relates more specially to that class thereof which are shown and described in an application for Letters Patent of the United States filed by me on the tenth day of February, A. D. 1915, Serial No. 7435. In said application there is set forth a structure wherein it is possible to convey a current of outside air into the fire-box and deliver the same immediately above the bed of coals therein. A part of the means for doing this consists of a pipe projecting downwardly into the fire-box, and on account of the extreme heat therein it is considered advisable to protect such pipe by means of a water-jacket or drum closed at its lower end and communicating at its upper end with the main supply of water in the boiler. To prevent sediment from accumulating in the water drum and interfering with the effectiveness thereof I provide means of communication between the lower end of said drum and the water spaces in the boiler at the sides thereof. A circulation of water through the drum is thus provided for, and the same kept free from obstruction.

In the drawings, the figure is a partial cross-section of a boiler equipped with my invention.

1 represents a boiler of usual construction and 2 the fire-box thereof, from which flues 3 extend rearwardly through the boiler. 4 is the masonry or shell in which the boiler is inclosed and 5 a part of the front plate thereof.

Within the shell 4 just above the boiler is an air-compartment 6, into which air is introduced through one or more pipes 7, and projected downwardly from the chamber 6, through the boiler 1 and into the fire-box is a pipe 8, the lower end of which is just above the fuel supply in the fire-box. A current 50 of air is introduced through such pipe and

distributed over the coals, aiding in the combustion thereof.

To prevent the projecting part of the pipe 8 from being injured or destroyed by the great amount of heat in the fire-box, I inclose the same in a drum 9, closed at its lower end, and open at the upper end, so as to communicate with the space in the upper part of the boiler, and receive a supply of water therefrom. To prevent the water in the drum 9 from being "dead", and sediment accumulating therein, a pair of pipes 10 is provided, connecting the lower end of said drum with the spaces 11 in the sides of the boiler. A circulation of the water through such drum and pipes takes place, keeping the same free from any obstruction, and permanently effective for the purpose for which it is provided.

While the devices shown and described in said former application relate more specially to the supply of a current of super-heated air or other fluid to the fire-box, it is obvious that the protective devices herein set forth are equally useful and effective in connection with the introduction of a current of cold air, if the same be considered preferable, and that the same can be employed in any case of the introduction of air, gas, etc., into the fire-box by means of a projecting pipe or similar means, which would be liable to injury from the excessive heat of the flames in the fire-box.

What I claim as my invention and desire to secure by Letters Patent of the United States, is:

1. A device of the class described, comprising a boiler; a fire-box therein; an air-chamber supported above the fire-box; means for introducing a supply of air into said air-chamber; a pipe projected from said air-chamber into the fire-box; and a water-drum inclosing that part of said pipe which extends into the fire-box, and communicating with the main body of water in said boiler.

2. In a device of the class described, a boiler; a fire-box therein; an air-chamber supported above said fire-box; means for introducing a supply of air into said air-chamber; a pipe projected from said air-

chamber through the boiler and into said fire-box; a water-drum, inclosing that portion of said pipe which extends into the fire-box, and communicating at its upper end 5 with said boiler; and means of communication between the lower end of said water-drum and said boiler.

In testimony whereof I affix my signature in presence of two witnesses.

MICHAEL JOSEPH CARNEY.
